UNITED STATES PATENT OFFICE.

HENRY J. NOTZ AND GEORGE A. REEVE, OF MIDDLETOWN, OHIO.

EXPANSIBLE CHUCK.

1,191,092.

Specification of Letters Patent.

Patented July 11, 1916.

Application filed March 7, 1916. Serial No. 82,714.

To all whom it may concern:

Be it known that we, HENRY J. NOTZ and GEORGE A. REEVE, citizens of the United States, residing at Middletown, in the county of Butler and State of Ohio, have invented certain new and useful Improvements in Expansible Chucks, of which the following is a specification.

The present invention relates to improvements in expansible chucks for centering and holding tubular work.

An important object of the invention is to provide apparatus of the above mentioned character, which is simple in construction, convenient in use and reliable in operation.

Other objects and advantages of the invention will be apparent during the course of the following description.

In the accompanying drawings forming a part of this specification and in which like numerals are employed to designate like parts throughout the same,

Figure 1 is a central longitudinal sectional view through apparatus embodying the invention, Fig. 2 is a transverse sectional view taken on line 2—2 of Fig. 1, Fig. 3 is a detail section taken on line 3—3 of Fig. 1, Fig. 4 is a side elevation of the entire apparatus, and, Fig. 5 is a detail section through the outer end of one jaw.

In the drawings, wherein for the purpose of illustration is shown a preferred embodiment of our invention, the numeral 5 designates a support or stand, which may be attached to a lathe or the like. This support or stand is provided with upstanding knuckles 6, for a purpose to be described. The stand 5 is provided near its forward edge with a screw-threaded opening 7, receiving an adjustable stop screw or element 8, projecting upwardly beyond the same, as shown.

The numeral 9 designates the tubular body portion of the chuck, having a longitudinally extending bore 10. The lower end of the tubular body portion 9 is closed by a reduced and exteriorly screw-threaded portion 11, which engages within a screw-threaded opening formed in a base 12. This base is provided with a horizontal knuckle 13, adapted to be arranged between the knuckles 6, and having a cylindrical open-

ing 14. The body portion 9 is provided near its upper end with an exhaust port 15, adapted to communicate with the atmosphere and at its lower end with an exhaust port 16, to communicate with the atmosphere. Arranged upon the top of the tubular body portion 9 is a cap 17, held thereon by screws 18 or other suitable devices.

The tubular body portion 9 is provided near its upper and lower ends with preferably equidistantly spaced horizontal radial openings 19, there being three of these openings in each set. Mounted to reciprocate within each set of openings 19 are three reciprocatory or expansible clamping jaws or bolts 20, as shown. The jaws 20 are provided at their outer ends with transverse grooves 21, receiving a curved leaf spring 22. The ends of this leaf spring are bent inwardly, forming hooked portions 23, disposed within one of the grooves 21, and extending into a depression 24 thereof. The function of this spring is to normally hold the jaws 20 in the inner position and return them to this position and to hold them against turning movement upon their longitudinal axes.

Mounted to reciprocate within the bore 10 of the body portion 9 are pistons 25, having their outer ends tapered and decreasing in diameter outwardly, to contact with the inner or inclined tapered ends of the jaws 20, as shown. The pistons 25 are provided with longitudinally extending surface grooves 27, receiving the inner ends of stop pins 28, which restrict the longitudinal movement of the pistons and also prevent their rotation. Arranged upon the inner ends of the pistons 25 are suitable packing devices 29, secured thereto by eye-bolts 30. These eye-bolts have connection with a retractile coil spring 31, serving to move both pistons 25 inwardly, upon the reduction of pressure therebetween.

Having communication with the chamber 32 between the inner ends of the pistons 25 is a longitudinally extending port 33, formed in the body portion 9. At its lower end, the port 33, communicates with a horizontal port 34, which leads into the cylindrical opening 14.

Extending through the apertured knuckles

6 and the opening 14 is a pipe or tube 35, which serves to pivotally connect the body portion 9 with the support 5. The pipe 35 is stationary and one end thereof is connected with a pressure supply conduit. As more clearly shown in Fig. 3, the pipe 35 is provided with a plug 37, dividing the same into an inlet portion 38 and an outlet portion 39. The inlet portion 38 of the pipe 35 has an opening or port 40 adapted for registration with the port 34, when the body portion 9 is swung to the vertical position, as clearly illustrated in Fig. 1. When this takes place, pressure is supplied to the chamber 32, as is obvious. Communicating with the exhaust portion 39 of the pipe 35 is a surface groove 41, the free end of which is in circumferential alinement with the port 40 but of course has no communication therewith. The free end of this groove 41 is adapted to communicate with the port 34, when the body portion 9 is swung to an approximately horizontal position, thus allowing the pressure within the chamber 32 to exhaust to the atmosphere.

The numeral 42 designates the work, which is of tubular construction, as shown. In the use of the device, the body portion 9 is moved to a more or less horizontal position, whereby the chamber 32 exhausts to the atmosphere or has no communication with the source of pressure. The work 42 may then be placed upon the body portion 9 and the work and body portion swung to the vertical position. When the vertical position is reached, which may be defined by the adjustment of the screw 8, the port 40 will register with the port 34 and pressure, such as compressed air, will pass through the inlet portion 38 of the pipe 35, port 40, port 34 and port 33 into the chamber 32. This pressure will move the pistons 25 outwardly and their tapered ends 26 will expand the jaws 20, causing them to move outwardly into clamping contact with the work. To remove the work the body portion 9 is swung to the horizontal position, whereby the port 34 is moved out of registration with the port 40 and into registration with the free end of the groove 41. The pressure will now exhaust from chamber 32, through port 33, port 34, groove 41 and through the outlet portion 39 of the pipe 35 to the atmosphere. The spring 31 will now move the pistons 25 inwardly, allowing the jaws 20 to move inwardly under the action of the springs 22. The work 42 may now be conveniently removed.

It is to be understood that the form of our invention herewith shown and described is to be taken as a preferred example of the same, and that various changes in the shape, size, and arrangement of parts may be resorted to without departing from the spirit

of the invention or the scope of the sub- 65 joined claims.

Having thus described the invention, we claim:

1. In an expansible chuck of the character described, a tubular body portion having sets of approximately radial openings formed therein which are longitudinally spaced upon the tubular body portion, jaws mounted to slide within the approximately radial openings, a pair of pistons mounted 70 to move longitudinally within the tubular body portion and adapted to contact with the sets of jaws to move them outwardly, and means for introducing pressure into the tubular body portion between the pistons to effect their movement.

2. In an expansible chuck of the character described, a tubular body portion having spaced sets of approximately radial openings formed therein and a pressure supply port discharging into the interior of the tubular body portion between the sets of approximately radial openings, jaws mounted to slide within the approximately radial openings, a pair of pistons mounted within 85 the tubular body portion upon opposite sides of the outlet end of the pressure supply port to be moved in opposite directions by the pressure and adapted to move the jaws outwardly, and means to supply pressure to the ports.

3. In an expansible chuck of the character described, a tubular body portion having sets of radial openings formed near the ends thereof, jaws mounted to slide within the 100 radial openings, a pair of pistons mounted to move within the tubular body portion and having inclined portions to contact with the jaws to move them outwardly, a retractile coil spring connecting the inner ends of 105 the pistons to move them toward each other, and means to supply pressure into the tubular body portion between the pistons.

4. In an expansible chuck of the character described, a tubular body portion having 110 radial openings formed therein, jaws mounted to slide within the radial openings, a piston mounted to move within the tubular body portion to contact with the jaws and move them outwardly, a base means pivotally connecting the tubular body portion and base, and means to supply pressure into the tubular body portion upon the swinging of the tubular body portion to the end of its travel in one direction with relation to the base. 115

5. In an expansible chuck of the character described, a tubular body portion having a radial opening formed therein, a jaw mounted to move within the opening, a piston mounted to slide within the tubular 125 body portion to operate the jaw, a base secured to one end of the tubular body portion and having a circular opening commun-

cating with a port which leads to the interior of the tubular body portion, a support, and a pipe attached to the support and extending through the circular opening of the 5 base, to pivotally connect the tubular body portion and support, said pipe having a plug dividing the same into inlet and exhaust portions and separate ports communicating with the inlet and exhaust portions 10 and adapted to be alternately moved into

registration with the port formed in the base.

In testimony whereof we affix our signatures in presence of two witnesses.
